UNITED STATES PATENT OFFICE.

THOMAS HENRY RAMMEL, OF PLAINVILLE, MASSACHUSETTS, ASSIGNOR TO WHITING
& DAVIS COMPANY, A CORPORATION OF MASSACHUSETTS.

BAG CLASP.

Application filed February 7, 1922. Serial No. 534,691.

To all whom it may concern:

Be it known that I, THOMAS H. RAMMEL, a citizen of the United States, residing at Plainville, in the county of Norfolk, State 5 of Massachusetts, have invented certain new and useful Improvements in Bag Clasps; and I do hereby declare the following to be a full, clear, and exact description of the invention, such as will enable others skilled 10 in the art to which it appertains to make and use the same.

This invention relates to hand bags, purses and in general to bags of the type having frame members to which cloth, leather or 15 other material composing the body of the bag is secured. More particularly the invention relates to a clasp device for securing the frame members of the bag together when the bag is closed.

20 The clasp device, in accordance with the invention, includes a rotatable member mounted on one of the frame members, which is adapted to coact with the other of the frame members to secure the frame 25 members together when occupying certain angular positions, and to release the frame members so that they may be opened when the rotatable member is turned to other angular positions. In accordance with one 30 form of construction, the rotatable member on one of the frame members is in the form of a pin of cylindrical or rounded form, having a depression or clearance therein, and the other frame member is provided 35 with a projection or lug which is adapted to pass through the depression or clearance when the rotatable member is in one angular position and to interlock with the rotatable member when the latter is turned to another 40 angular position. The rotatable member is normally yieldably held in the locking position by means of a spring.

Where the bag frame has a bail as is common in various forms of bags to provide 45 means of suspension, the rotatable member is conveniently made a part of the bail construction so that by rotating the bail in one direction or the other the rotatable member is turned to the locking or 50 open position, as the case may be.

The frame members of the bag are usually hinged and preferably have springs so positioned and arranged on the members that they tend to force the members open and

retain them in open position after they are 55 released by operation of the clasp device.

In the preferred construction of the clasp device the bail is normally positioned substantially in the plane of the member on which it is mounted, means such as a spring 60 being preferably provided to retain the bail in this position. So positioned the bail is adapted to lock the frame members together. The open positions of the bail are arranged at angles approaching and approximately at 65 an angle of 90° to the plane of its supporting frame member, while angular positions intermediate the latter and the normal position are locking positions. This arrangement of angular positions for effecting locking 70 and opening of the frame members is of advantage in precluding the possibility of accidental opening of the bag while being carried, when danger of loss of the contents of the bag would be greatest. While carried, the bag is suspended from a chain or strap by means of the bail, and so gravity assists the spring or other means provided for retaining the bail in its normal position in the plane of its supporting frame 75 member; and, although the bail might be moved slightly from this position as it is carried, the deviation would be well within the range of angular positions in which the bail is adapted to lock the frame members 80 together.

The invention is illustrated in the accompanying drawings in application, as an example, to a hand bag or purse. In the drawings—

Fig. 1 illustrates the frame of a bag with the clasp device for securing the frame members together;

Fig. 2 is a view along the line 2—2 of Fig. 1 and shows the frame members of the bag locked together by the clasp;

Fig. 3 is a view similar to Fig. 2 showing the open position of the clasp device for releasing the frame members so that they may be opened; and

Fig. 4 is a view along the line 4—4 of Fig. 2.

Referring to the drawings, the frame 5 of the bag consists of a pair of frame members 6 and 7 which are hinged together at 8, the hinges carrying springs 9 which tend to force the frame members open and to retain them in open position. Mounted at the apex

of the frame member 7 is a bail 10 to which the usual chain or strap 11 provided for carrying the bag is secured. Forming a part of the bail 10, and serving as a pivot 5 therefor, is a pin 12 of cylindrical or rounded form which is mounted for rotation in a sleeve 13 secured to the frame member 7. This rotatable pin has a portion of its surface so formed that, in certain angular positions, it provides a stop for a projecting lug on the other frame member and another portion of its surface so formed that, in one angular position of the pin, it provides a clearance whereby the lug is released. For 10 this purpose the pin 12 has, intermediate its ends, a depressed portion 14 which is best illustrated in Fig. 4. Secured to the frame member 6 is a lug or clasp member in the form of a ball clasp 15 which is in alignment with the depressed portion 14 in the surface of the pin 12. The ball portion 16 of the member 15 has a slight concavity 17, fitting the cylindrical or rounded surface of the pin 12.

25 The bail 10 is normally held in a position substantially in the plane of the frame member 7, to which it is secured, by means of a pair of coil springs 18 situated within the sleeve 13. These springs are mounted one 30 at each end of the pin 12, the outer ends of the springs being fitted in slots 19 formed in a projection on each of the sleeve caps 20 by which the springs are rigidly held against rotation, and the other ends of the springs 35 are fitted in slots 21 formed in the reduced end portions 22 of the pin. In the normal position of the bail the cylindrical or rounded portion of the pin 12 is uppermost and, with the lug 15 in locking position, as when 40 the frame members are together, the cylindrical surface engages the concavity 17 in the lug to lock the frame members together as is illustrated in Fig. 2. The open position of the clasp device is illustrated in Fig. 45 3 and in this position the bail is substantially at an angle of 90° to the frame member 7 on which it is mounted. It will be evident from an inspection of Figs. 2 and 3 that the bail may be rotated an appreciable 50 amount to different angular positions with respect to the frame member 7 before the ball 16 of the clasp member 15 will be disengaged therefrom and the depressed portion or clearance 14 brought opposite the lug 55 to effect its release. Similarly various angular positions of the bail with respect to the frame member 7 are possible in the open position of the clasp device; that is to say, before the surfaces of the pin and lug are 60 brought into interlocking engagement.

Before the frame members can be brought together to close the bag, the bail must be rotated to a position to bring the depressed portion 14 of the pin opposite the ball portion 16 of the lug. When the parts are po-

70 sitioned relatively to each other in the manner, the ball 16 of the lug may freely pass over the pin 12 as in the position of the parts illustrated in Fig. 2 when the frame members are closed. With the lug in this position, the frame members are locked together by rotating the bail in the opposite direction to that necessary to disengage the pin and lug, and by continuing the rotation of the bail the outer cylindrical surface of the 75 pin is brought in contact with the concavity 17 in the ball portion 16 of the lug and these parts are securely locked together.

75 For carrying the bag, suspension means are provided as has already been noted, such 80 means in the present instance consisting of the bail 10, to which is attached a chain or strap 11.

I claim:

1. A bag frame comprising a pair of 85 frame members, and a clasp device therefor, including a rotatable member on one frame member, a projection on the second frame member adapted to overlie and engage said rotatable member, the latter having a portion of its outer surface formed to provide a stop abutting against said projection when held in one angular position relative thereto, and another portion of its outer surface formed to provide a clearance when turned to another angular position for releasing said projection so that the frame members 90 may be opened.

2. A bag frame comprising a pair of 95 frame members, and a clasp device therefor, including a rotatable member on one frame member having a portion of reduced cross-section and a projection on the other frame member which is adapted to be moved across 100 said portion to overlie said rotatable member, when the rotatable member is in one angular position and, which is adapted to interlock with the rotatable member when the latter is in another angular position.

3. A bag frame comprising a pair of 110 frame members, and a clasp device therefor, including a rotatable member on one frame member having a depression therein, and a projection on the other frame member which is adapted to pass through said depression 115 when the rotatable member is in one angular position, and which is adapted to interlock with the rotatable member when the latter is in another angular position, and a bail secured to the rotatable member and 120 having suspension means for the bag secured thereto.

4. A bag frame comprising a pair of 125 frame members, and a clasp device therefor, including a rotatable member on one frame member having a depression therein, and a projection on the other frame member which is adapted to pass through said depression 130 when the rotatable member is in one angular position, and which is adapted to interlock

with the rotatable member when the latter is in another angular position, and a spring for holding the rotatable member yieldingly in its interlocking position.

- 5 5. A bag frame comprising a pair of frame members, and a clasp device therefor including a bail pivotally mounted on one of said frame members, and means tending to hold said bail in a position normally in 10 the plane of said member, said bail having a rotatable member serving as a pivot therefor and adapted to coact with a projection of the other frame member to lock said frame members together when said bail is in its 15 normal position, to unlock said frame members when rotated to positions approaching and at an angle of 90° with the plane of the member on which the bail is mounted, and to maintain said frame members in a locked 20 condition at intermediate positions.

6. A bag frame comprising a pair of frame members, and a clasp device therefor including a sleeve secured to one of said members, a clasp member secured to the

other of said members, and a bail having 25 a pin pivoted in said sleeve in cooperation with which said clasp member is adapted to act to lock said frame members together in certain positions of the bail, and to release the clasp member and unlock the frame 30 members when the bail is moved to certain other positions.

7. A bag clasp comprising a pair of frame members, and a clasp device therefor, including a rotatable member on one frame 35 member having a depression therein, and a projection on the other frame member which is adapted to pass through said depression when the rotatable member is in one angular position, and which is adapted to interlock with the rotatable member when the latter is in another angular position, and a pair of oppositely acting springs engaging one of the frame members and the rotatable member for holding the rotatable member 40 45 yieldingly in its interlocking position.

In testimony whereof I affix my signature.
THOMAS HENRY RAMMEL.
